METHOD AND APPARATUS FOR PACKAGING BEVERAGES

Robert J. Stewart, Baltimore, Md., assignor to
Crown Cork & Seal Company, Inc., Baltimore,
Md., a corporation of New York

Application December 19, 1939, Serial No. 310,048

6 Claims. (Cl. 226—72)

The present invention relates to methods and apparatus for packaging beverages and, more particularly, a method and apparatus for packaging beer or other carbonated beverages in such a manner that air will be at least substantially excluded from the head space of the bottle or other container.

Carbonated beverages such as beer are ordinarily flowed into containers in open atmosphere and it is customary to fill the containers only to a point some distance below the mouth thereof, with the result that the head space of the container will contain air. When the container subsequently has a cap applied thereto, this air will be sealed in the head space. The presence of air in the head space of a container is altogether undesirable in its effect upon beer and other carbonated beverages and numerous apparatus and methods have been developed for the purpose of excluding such air before the container is sealed.

A very convenient manner of excluding air from containers is disclosed in the patent to Horace H. Fisher, 2,046,256, June 30, 1936, for Method and apparatus for liberating air from receptacles containing carbonated beverages. The Fisher patent discloses an arrangement whereby after a bottle or other container has been filled, the bottle is tapped or otherwise vibrated or agitated so that the carbonated contents, ordinarily beer, will be agitated. Such agitation of the beverage causes foam to rise from the same with the result that the head space will be filled with a fine foam and all air forced upwardly from the head space. The degree of agitation imparted to the container is such that by the time the container has reached the capping mechanism, the foam will have risen to a point very slightly above the mouth of the container so that no more air will remain in the head space and the foam above the mouth of the container will even exclude air from the interior of the cap as the latter is applied.

A difficulty encountered in the use of the apparatus and method of the Fisher patent is that the wall of a glass container may vary in thickness circumferentially of the container. That is, at one point in the circumference of the container the wall may be somewhat thicker than at a substantially diametrically opposite point. The degree of force of the tapping or agitation imparted to the container by the Fisher device must of course be gauged so that only sufficient carbon dioxide will be liberated from the beverage that foam will merely rise to a point very slightly above the mouth of the container and particular

difficulties have been met in creating exactly the desired extent of foaming. If the tapping element, set to strike a blow of a certain force, comes into contact with a thin portion of the wall of a container, too much foam will be created and uncontrollable foaming may occur. Uncontrollable foaming, as well as too much foam, will result in waste of beverage. On the other hand, if the tapping element comes into contact with a thick portion of the container, the beverage will not foam to the desired extent and will only rise to a point below the mouth of the container so that some air will be certain to remain in the head space.

15 An object of the present invention is to provide a method and apparatus whereby substantially all air will be excluded from the head space of glass containers, regardless of variance of the thickness of the container walls.

20 Another object of the invention is to provide a container vibrating or tapping device which can be readily and conveniently applied to a filling machine and which can be conveniently adjusted to vary the vibration imparted to a container.

25 A still further object of the invention is to provide an efficient method and apparatus for tapping all types of containers.

It has been found desirable to subject all types of containers, including those having walls of 30 uniform thickness throughout, such as metal containers, to two relatively light blows or vibrations, rather than to one heavy blow. More particularly, it has been found that a single blow of sufficient force to cause foam to rise above the container mouth may in some instances cause such a sudden, sharp foaming that uncontrollable foaming will result. By tapping the container a number of light blows, at spaced time intervals, sharp foaming cannot result and the foam will 35 rise by stages to the desired extent. This is a particular advantage with beer, due to its tendency to uncontrollable foaming.

40 Other objects and advantages of the invention will be apparent from the following specification and drawings wherein

Figure 1 is a fragmentary plan view of a filling machine having the present invention applied thereto.

Figure 2 is a horizontal sectional view of the tapping mechanism of Figure 4.

Figure 3 is a horizontal sectional view of the tapping mechanism of Figure 4 on a lower plan than the section of Figure 2.

Figure 4 is a vertical sectional view on the 45 angled line 4—4 of Figure 1.

Figure 5 is a side elevation of a tapping mechanism.

Figure 6 is a vertical sectional view on the line 6—5 of Figure 5, and

Figure 7 is a horizontal sectional view on the line 7—7 of Figure 5.

Referring to Figure 1, the filling machine there illustrated is of well-known type comprising a stationary table 10 having its inner edge 11 of arcuate form and a rotating filling table 12 having its forward periphery positioned closely adjacent the arcuate edge 11 of the stationary table in the usual manner. The filling table 10 is provided adjacent its periphery with a plurality of bottle supporting platforms 13, each having a filling head 14 above the same. The stationary table 10 includes a means to position bottles upon the bottle supporting platforms 13 of the filling table during the rotation of the latter and also includes a transfer dial 15 which removes the bottle from each platform 13 and transfers it across the upper surface 10a of the stationary table to the capping mechanism 16. From the capping mechanism the bottle moves to the usual straight line conveyor 17 which conducts the bottle from the machine.

The stationary table has a guide plate 18 superimposed thereon, the edges of the guide plate adjacent the transfer dial 15 and the crowning mechanism 16 being of arcuate outline so as to guide containers moving in the pocketed dials of these mechanisms. As is usual, a skirt 19 depends from such edges of the guide plate toward the surface 10a of the stationary table. The guide plate 18 includes a portion 20 projecting outwardly over the bottle supporting platforms and beneath the outwardly projecting container engaging arms provided on these platforms as disclosed in the divisional application of Robert J. Stewart and Wiltie I. Gladfelter, Serial No. 128,300, filed February 27, 1937, for Filling machine.

The filling machine illustrated in Figure 1 is provided with two tapping mechanisms 21 and 38. The tapping mechanism 38 is mounted adjacent the transfer dial 15 so that it will tap a container after the latter has been placed upon the stationary table 10 and is engaged by the transfer dial. As will be subsequently explained, in a filling machine of the type disclosed, each container is bodily rotated substantially 180 degrees during its movement from the filling table to the stationary table and the two tapping mechanisms are so located with respect to each other that the second tapping mechanism 38 will tap the container at a point circumferentially spaced from the point at which it was tapped by the tapping mechanism 21.

The tapping mechanism 21 is preferably mounted at the inner end of a valve trip supporting arm and as shown in Figures 5 and 6 comprises a hollow base portion 23 having a vertical rod 24 clamped therein by a bolt 25 so that the rod may be vertically adjusted with respect to the base portion. The rod has a shoulder 26 formed thereon at a point spaced from its upper end and a sleeve 27 is rotatably mounted upon rod 24 above the shoulder, preferably with an anti-friction element positioned between the lower end of the sleeve and the shoulder. Above the upper end of the sleeve a clamp 28 is secured to the arm, the clamp being of split form and including a bolt 29 so that its position circumferentially of the rod 24 may be adjusted. A nut 30 bears upon the clamp 28. A coil spring 31

surrounds the upper portion of sleeve 27, this portion of the sleeve preferably being reduced in diameter. The upper end of spring 31 is secured to the clamp 28 and the lower end is secured to the sleeve 27. The sleeve 27 includes a radially projecting portion 33 which is split as shown to receive a tapping arm 32. Due to the split formation of the projecting portion of the sleeve, the position of the tapping arm 32 therein may be adjusted and held in adjusted position by a bolt, as shown.

It will be observed from Figure 1 that the tapping arm 32 will normally be in a position extending substantially radially with respect to the filling table 12 so that as a bottle or other container B comes into contact with the tapping arm 32 it will swing the latter in a counter-clockwise direction against the action of the coil spring 31. After that bottle has moved past the end of the arm 32, the latter will move backwardly to impart a tap to the succeeding bottle and the latter, in turn, will swing the arm 32 in a counter-clockwise direction in readiness to tap the following bottle.

As shown in Figures 1, 2 and 4, the tapping mechanism 38 includes a bracket or base portion 40 secured to the upper surface of the guide plate 18 on the stationary table 10 and which has a housing 41 extending therefrom including a downwardly facing recess 42 provided with an aperture in which a downwardly extending post 44 is mounted, post 44 being secured against rotation in the aperture by means of a nut 45 engaging its upper and threaded end. The post 44 is slightly enlarged in diameter as at 46 immediately below the lower surface of the recessed portion and carries a worm wheel 47 which is separated by a washer 47a from the shoulder at the upper end of the larger and lower portion of the post. The lower portion of the post has a sleeve 48 rotatably mounted thereon and a coil spring 50 surrounds the upper and reduced portion of the sleeve with its upper end secured to the worm wheel 47, while its lower end is secured to the lower and enlarged end of the sleeve 48. The sleeve includes at its lower end a projection which is apertured and split as at 52 to receive a tapping arm 51. An anti-friction element is preferably positioned between the lower end of the sleeve and the lower and preferably shouldered end 49 of the post.

The tapping arm 51 extends through a slot 58 in the depending skirt 19 of the guide plate 18 and the tension exerted upon the spring will normally urge the tapping arm in a counter-clockwise direction so that it will contact with the end 59 of slot 58 nearest the rotary filling table 12. When a container B contacts with the tapping arm 51 the latter will be swung backwardly in a clockwise direction so that its end will lie substantially flush with the skirt 19 and, when the container has moved clear of the end of the tapping arm the latter will swing backwardly under the force of the spring to strike the following container.

Due to the fact that the filling table is rotating with respect to the stationary table, each container will be rotated substantially 180 degrees during its transfer from position B² on a bottle supporting platform to position B' on the stationary table, such rotation of course being due to the fact that one portion of the base of the container will contact with the stationary table while the remaining portion is still bear-

ing upon the bottle supporting platform, with the latter moving along the stationary table. For that reason, even though both tapping arms strike the container from a point directly in advance of its linear movement, the point at which the two arms strike the container will be spaced substantially half-way about the container. Thus the container will be struck at two different points and the total vibrational or tapping force imparted to the container will be the proper force to cause sufficient carbon dioxide to be liberated from the beverage to result in foaming to exactly the desired extent. Because of this, each container will receive the proper tapping effect, regardless of whether the thickness of the wall may vary.

In handling glass containers or other containers which may vary in thickness, the two tapping devices 21 and 38 will be set to impart the proper total blow or vibration to a container of minimum thickness at diametrically opposite points. Therefore, if the container is thick at one of these points or is of proper diameter at both points, the total tapping effect will be sufficient to cause foam to rise to a point very slightly above the mouth of the container. A container which is thin at both points would theoretically receive a slightly more forcible tapping than is desired but such a glass container does not occur. That is, each glass container includes a fixed amount of glass distributed throughout its side walls and since the amount of glass is constant, the walls of the container will never be thin throughout its entire diameter but will either be of average thickness throughout the circumference or thicker at one point than at another. As a result, and as stated above, by tapping the container at preferably diametrically spaced points the total tapping force will be proper if the two tapping devices are each set to strike the proper blow needed to properly agitate a container which is thin throughout its diameter.

In order that the tapping device 38 which is spaced inwardly from the front edge of the machine may be conveniently adjusted, a worm gear 53 is journaled in the housing 44 so that it will mesh with the worm wheel 47, the forward end of the shaft 54 of the worm gear being connected by a universal joint 55 to a rod 56 extending to the front edge of the machine and supported in brackets upon the upper surface of the guide plate 18. The rod 56 is provided with a handle 57 at its forward end so that it may be rotated to adjust the position of the worm wheel 53 and thereby adjust the tension upon the coil spring 50. Due to the universal connection, the housing and the adjusting shaft can be mounted at the desired angle upon filling machines of various types and sizes so that the tapping arm will always be properly positioned with respect to various containers and the operating handle 57 will be at a convenient angle with respect to the machine. The tapping mechanism 21, being immediately adjacent the side of the machine, can be conveniently adjusted by adjusting the position of the clamping bracket 28.

The multiple tapping of the present invention is also particularly efficient with containers of such type as to have their walls of uniform thickness throughout their diameter, as is the case with metal containers. When operating upon such containers the two arms would have the tension of their springs adjusted so as to administer

a sufficient total vibration that the beverage will foam to the proper point. It is found that the administering of two light blows, preferably at different points on a container, gives a finer foam and obviates the possibility of uncontrollable foaming which may result from a single heavy blow. A fine foam is desirable because it forms a dense rising foam blanket which more thoroughly drives out the air. The advantage of multiple tapping to eliminate a sharp blow is, of course, concurrently obtained with containers having their walls non-uniform.

Ordinarily, the tapper 21 will be maintained set to strike a fixed blow and the tapper 38 will be adjusted as desired for a particular run of bottles or beverages. The construction of tapper 38 to permit it to be finely adjustable over a wide range, as well as the accessibility of its operating handle enables it to be readily adjusted to cooperate with tapper 21 to give exactly the desired total tapping effect.

It will be understood that, instead of the tappers disclosed herein and by means of which an advance bottle actuates the tapper so that a succeeding bottle will be struck, the present mechanism may be constructed with tapping arms of the type shown in the Fisher patent, wherein the same bottle which actuates the tapper receives the tapping blow.

The terminology employed in the specification is for the purpose of description and not of limitation, the scope of the invention being defined in the claims.

I claim:

1. The method of packaging beverages containing carbon dioxide which comprises partially filling a container with the beverage in an atmosphere containing air whereby the space in the container above the beverage will contain air, vibrating a plurality of substantially diametrically opposed portions of the container to cause a portion of the carbon dioxide to be liberated and thereby displace at least a part of the air in the container above the liquid, and then sealing the container.
2. In combination, means to partially fill a container with a beverage containing carbon dioxide and in an atmosphere containing air whereby the space above the beverage will contain air, closure applying means, means for moving the container from said filling means to said closure applying means, and means for vibrating the container at two substantially diametrically opposed portions thereof during such movement to cause a portion of the carbon dioxide to be liberated and thereby displace at least a part of the air in the container above the liquid.
3. In combination, closure applying means, means to partially fill a container with a beverage containing carbon dioxide and in an atmosphere containing air whereby the space above the beverage will contain air and for moving the container to said closure applying means while bodily rotating the container about its vertical axis, and a pair of means for vibrating the container during such travel, said vibrating means being positioned at such points in the linear path of travel of the container as to contact with two circumferentially spaced portions of the container to cause a portion of the carbon dioxide to be liberated and thereby displace at least a part of the air in the container above the beverage.
4. In combination, means to partially fill a container with a beverage containing carbon dioxide and in an atmosphere containing air whereby the

space above the beverage will contain air, closure applying means, means to impart a partial rotation to the container on its vertical axis, means to move the container from the point of bodily rotation to said closure applying means, and means to vibrate the container before and after such bodily rotation to cause a portion of the carbon dioxide to be liberated and thereby displace at least a part of the air in the container above the beverage.

5. In a filling machine, the combination of a rotating filling table, a stationary table, means to move containers from the filling table and across the stationary table, a guide member partially encircling said last-named means, said plate including a depending skirt extending alongside the path of the containers, said skirt having

a longitudinally extending slot therein, and a spring tensioned tapping arm pivotally mounted to extend through said slot into the path of the containers.

- 10 6. In combination, means to partially fill a container with a beverage containing carbon dioxide and in an atmosphere containing air whereby the space above the beverage will contain air, means to rotate the container on its vertical axis, and means to impart vibrations to two substantially diametrically opposed points of the container during such rotation to cause a portion of the carbon dioxide to be liberated and thereby displace at least a part of the air in the container above the beverage, and means to seal the container.

ROBERT J. STEWART.
